UNITED STATES PATENT OFFICE.

ABRAM C. MOTT, JR., OF LANSDALE, AND CHARLES H. WHEAWILL, OF PHILADELPHIA, PENNSYLVANIA, ASSIGNORS TO ABRAM COX STOVE COMPANY, OF LANSDALE, PENNSYLVANIA, A CORPORATION OF PENNSYLVANIA.

COMBUSTION RING FOR FURNACES.

Application filed March 10, 1926. Serial No. 93,701.

The object of our invention is to provide a combustion ring for a furnace, in which the fire-brick or hollow cast-iron sections can be readily placed in position or removed for re-pairs without dismantling the furnace structure.

Further objects and advantages of our invention will be apparent from the accompanying drawings, in which

10 Fig. 1 is a plan view, partly in section, on the line 1—1, Fig. 2, of a household boiler furnace, and illustrating our invention;

Fig. 2 is a vertical sectional view of the combustion ring on the line 2—2, Fig. 1;

15 Fig. 3 is a sectional view of the ring on the line 3—3, Fig. 1;

Fig. 4 is a perspective view of one of the fire-bricks lining the combustion ring;

20 Fig. 5 is a detached perspective view of the half fire-brick which forms the key for holding the other fire-brick in position;

Fig. 6 is a perspective view of a water-back section which can be substituted for one of the fire-brick sections at the back of the combustion ring; and

25 Fig. 7 is a view of a portion of the back of the ring, showing the water-back section located in position.

1 is the base section of the boiler structure containing the ash-pit. 2 is the combustion ring, and 3 is the upper section of the combustion chamber of the boiler or other heating apparatus. As the invention relates solely to the combustion ring, we have shown the other characters of the structure in outline.

30 The combustion ring 2 in the present instance is frusto-conical in shape, and has a base flange 14 which rests upon the base structure 1 and is secured thereto in the ordinary manner. At the upper end of the ring is an internal flange 4, while on the bottom section is a flange 5 having spaced teeth which form part of the grate section of the structure.

35 40 45 6 are fire-brick sections, shaped as shown in Figs. 1 and 4, and each brick is of a greater width at the base than at the top and is a segment of a complete circle. The brick 7 is the key brick, the bricks 6, when arranged in the ring, being held firmly in position by the key

brick 7. When, however, the key brick is removed, the remaining brick sections can be removed through the fire-pot and replaced without dismantling any other part of the furnace structure.

The key brick 7 is held in position by the frame 8, the latter having a clean-out opening therein. The opening in the frame 8 is closed by a door 9 hinged in the ordinary manner. The portion 10 of the frame 8 extends under the half fire-brick 7, and retains it in its raised position, locking all the other fire-bricks, but on removing the frame 8, the brick 7 can be lowered and then removed, as the space is wider at the bottom than the width of the half brick 7. When this half-brick is removed, all of the other full bricks can be readily detached and removed.

If it is desired to locate a water-back in the combustion ring, a water-back of the type shown in Fig. 6 can replace the rear fire-brick section. This water-back consists of a hollow cast metal section 11, to which are attached inlet and outlet pipes 12 and 13, communicating with a water circulating system. The pipes extend through notches 14' in the back 75 of the section 2 as clearly shown in Fig. 7. When the water-back is not used, the notches are covered by a plate 15.

In some instances, iron blocks may be used instead of the fire-brick shown, without departing from the essential features of the invention, these blocks being made in substantially the same shape as the fire-brick.

We claim:

The combination in a furnace, of a frusto-conical combustion ring; an opening in the lower portion of the ring; a detachable frame located in the opening; and a series of tapered bricks mounted in the ring, one of said bricks being a short key brick, said short key brick 85 90 being located above the frame, holding the other bricks in position and being removable through the space occupied by the frame when said frame is removed, said removable short key brick releasing the other bricks.
